UNITED STATES PATENT OFFICE.

FRED JOSEPH WILLIAMSON, OF DOVER, OHIO.

REFRIGERATOR.

1,379,500.

Specification of Letters Patent.

Patented May 24, 1921.

Application filed August 27, 1919. Serial No. 320,219.

To all whom it may concern:

Be it known that I, FRED JOSEPH WILLIAMSON, a citizen of the United States, residing at Dover, in the county of Tuscarawas and State of Ohio, have invented new and useful Improvements in Refrigerators, of which the following is a specification, reference being had to the accompanying drawings.

10 This invention relates to refrigerators, and has for its object to provide a refrigerating chamber that can be easily disassembled for cleaning.

Another object of the invention is to provide refrigerating means which permits a large circulation of air and permits the air to cool rapidly so that the melting of the ice caused by the entrance of warm air when the refrigerator door is opened, is 20 practically eliminated.

A still further object of the invention is to provide refrigerating means capable of obtaining more refrigeration from a quantity of ice than was possible before with 25 the same quantity of ice used in refrigerators previously proposed.

These objects are attained by the mechanisms illustrated in the accompanying drawings, in which:

30 Figure 1 is a perspective view of a refrigerator with the refrigerating chamber applied:

Fig. 2 is a longitudinal sectional view through the refrigerator and refrigerating chamber; and

35 Fig. 3 is a detail view of the means for fastening the cap to the lower end of the refrigerating chamber.

The invention consists of a refrigerator 40 5, which may be circular or square in construction and provided with the usual shelves 6. Hinged to the upper portion of the refrigerator is a cover 7, while a door 8 is hinged to the front portion of the refrigerator.

45 Removably mounted in the refrigerator 5, is a receptacle 9, intended to receive ice. This receptacle has its upper edge flared as at 10 which snugly engages the walls of 50 the refrigerator 5. Air passages 11 are formed in the receptacle adjacent the flared upper end and in the lower portion. Extending downwardly from the bottom of the receptacle 9, is a casing 12 intended to 55 receive cracked ice. A pan 13 is provided,

and is intended to receive the drippings from the receptacle 9. One edge is provided with a rod 13^a which is detachably connected to the receptacle 9 and holds the pan in spaced relation to the receptacle, 60 thereby providing an air chamber. Extending from the pan 13 is an outlet member 14 into which the casing 12 of the receptacle 9 projects, said casing being positioned in spaced relation to the sides of the 65 outlet member to permit free passage of drippings from the pan 13.

Detachably engaged with the outlet member 14 is a casing 15 also intended to receive cracked ice. Connected to one side of the 70 casing, is a plurality of hooks 16 adapted to engage eyes disposed within the refrigerator to hold said pan and casing in the proper position. The lower portion of said casing has a plurality of openings 17 which 75 are covered by wire mesh 18 to prevent the escape of ice into the refrigerating chamber. Disposed on the end of the casing 15 is a cap 19 intended to close said end. This cap is provided with a plurality of hooks 20 80 adapted to engage a plurality of hooks 21 carried by the casing 15 to hold the cap in place. Extending from the bottom of said cap adjacent one side is an outlet member 22 which permits the escape of drippings. 85

The different sections of this device are so arranged that they can be easily removed from the refrigerator and detached from one another for cleaning. Furthermore, it is adaptable to any form of refrigerator. 90

What is claimed is:

A refrigerator of the character described comprising a refrigerating chamber, an ice receiving receptacle having its upper marginal edge engaged with the upper edge 95 of the refrigerating chamber and its body portion disposed in spaced relation to the walls of said chamber, an ice receiving outlet casing projecting from the bottom of said receptacle, a supporting member depending from said receptacle, a pan disposed in spaced relation to the bottom of the receptacle and having one portion thereof supported by said supporting member, an outlet casing projecting from said pan remote from the supporting member and adapted to receive the end of the first mentioned outlet casing, said first mentioned outlet casing being disposed in spaced relation to the inner surface of the second 110

mentioned casing, and an ice receiving outlet casing extending to the lower portion of the refrigerating chamber, and being detachably connected to the wall of the chamber in spaced relation to the bottom thereof, the upper portion of the last mentioned casing being adapted to frictionally engage

and support the end portion of the second mentioned casing whereby said pan is held in the proper position.

10

In testimony whereof I hereunto affix my signature.

FRED JOSEPH WILLIAMSON.
